UNITED STATES PATENT OFFICE.

ALICE HENRIETTA DESSART, OF NOGALES, ARIZONA TERRITORY.

COMBINATION WEARING-APPAREL.

SPECIFICATION forming part of Letters Patent No. 770,562, dated September 20, 1904.

Application filed June 15, 1904. Serial No. 212,650. (No model.)

To all whom it may concern:

Be it known that I, ALICE HENRIETTA DESSART, a citizen of the United States, residing at Nogales, in the county of Santa Cruz and Territory of Arizona, have invented certain new and useful Improvements in a Combined Catamenial Sack, Hose-Supporter, Shield, and Bustle-Holder, of which the following is a specification.

- 10 My invention relates to improvements in protectors for female wearing-apparel, wherein I combine different articles, being a catamenial sack, hose-supporter, and an apron or shield, thus producing a single article; and 15 the invention consists in the novel construction, combination, and arrangement of parts of which it is composed, all as will be hereinafter more fully explained, and particularly pointed out in the appended claims.
- 20 The annexed drawings, to which reference is made, fully illustrate my invention, in which—

Figure 1 represents a plan view of my combination device, and Fig. 2 is a vertical sectional view of the same.

Referring by letter to the accompanying drawings, A designates the protector or combination wearing-apparel, comprising a belt a, an apron or shield b, hose-supporter c, and 30 a catamenial sack d. This belt, which buckles around the waist of the wearer, is provided in front and rear with vertical straps e and f, that are stitched at their upper ends to the belt, as at s s, and their free lower ends are 35 provided with fastening devices or "safety-pins" g g, adapted to engage and hold the front and rear ends of the catamenial sack d. Suspended from this belt are vertical straps or hose-supporters h h, which latter are also 40 stitched at their upper ends to the belt aforesaid, while their lower free ends are provided with clamps i i for engaging and holding taut the hose of the wearer.

Connected to the hose-supporters and the belt, through the medium of straps, is an apron or shield b, constructed of waterproof material, the same being worn in rear of the wearer, and the upper end of said shield is secured or stitched to an elastic horizontal 50 strap j, which in turn is secured at each end

k k to the vertical hose-supporters. A second and similar horizontal elastic strap l, but somewhat longer than the strap j, is arranged below the latter and secured at its ends k' k' to the hose-supporters as well as to the apron or shield, as shown at n. Interposed between the belt and the upper end of the apron or shield b are short vertical straps o, which are secured at their upper ends p to the belt, and at their lower ends the same are secured to 60 the upper edge of said shield, as at r.

Having thus described the different parts combined in a single article of which my device is composed, I will now explain its operation.

It will be readily observed from the above description, when taken in connection with the accompanying drawings, that in adjusting the article to the body of the wearer she first buckles the belt around her waist, after which 70 the opposite ends of the catamenial sack are attached to the lower ends of the front a rear vertical straps e f and the suppor' are secured to the hose in the usual man at the same time the shield is suspended rear of the wearer and supported by the sho. vertical straps secured to the belt, said shield being retained in position and prevented from lateral displacement by the elastic horizontal straps j l, which straps by their elasticity 80 permit free movement of the wearer's limbs, and said waterproof shield provides a sure protector at all times and will be beneath the wearer when in a sitting position, and when in a standing position in rear of the person, 85 thus shielding and protecting the clothing of the wearer from being soiled.

If desirable, the inner face of the shield may be provided with a covering of stockinet to prevent the shield from too close contact or 90 clinging to the wearer, and the straps and belt may be made of any suitable material, and a device as herein described is durable and inexpensive to manufacture.

Having described my invention, what I 95 claim, and desire to secure by Letters Patent, is—

1. The combination with the belt, sack-supporters and hose-supporters, of the shield, elastic horizontal straps and the vertical straps 100

whereby the shield is suspended from and supported by the belt substantially as described.

2. The combination with the belt, sack-supporters and hose-supporters of the horizontal elastic straps connecting said hose-supporters to one another, the shield stitched to said horizontal straps, and vertical straps, the latter secured at their upper end to the belt and at their lower end to the upper edge of the shield, whereby the latter is suspended from and supported by said belt, substantially as described.

3. The within-described combined catametrical sack, hose-supporters and protector or shield, consisting of the belt, provided with the front and rear straps for suspending the sack, the hose-supporters, connected at their upper end to said belt, and provided at their

lower end with the hose clasps or fasteners, the upper and lower horizontal elastic straps, arranged between the vertical hose-supporters, the apron or shield interposed between said hose-supporters and the vertical supporting-straps for the shield, the whole connected or stitched to one another as shown, providing a single article, for the purposes, substantially as described. 20 25

In testimony whereof I have signed my name to this specification in presence of two witnesses.

ALICE HENRIETTA DESSART
